(57) CLAIM

The ornamental design for a kitchen knife, as shown and described.

DESCRIPTION

FIG. 1 is right side elevation view of a kitchen knife according to the present invention, the left side being a mirror image thereof; and,

FIG. 2 is a back, top and right side perspective view of the kitchen knife depicted in FIG. 1.

The broken lines shown in FIGS. 1 & 2 are for illustrative purposes only and form no part of the claimed design.
